UNITED STATES PATENT OFFICE.

CANTNELL J. MOORE, OF WEBSTER, IOWA.

GATE.

SPECIFICATION forming part of Letters Patent No. 285,830, dated October 2, 1882.

Application filed May 4, 1883. (No model.)

To all whom it may concern:

Be it known that I, CANTNELL JONES MOORE, a citizen of the United States, residing at Webster, in the county of Keokuk and State of Iowa, have invented a new and useful Gate, of which the following is a specification, reference being had to the accompanying drawings.

This invention relates to gates; and it has for its object the construction of a fence-gate 10 in such a manner as will admit of its easy and convenient use by passers through the gate, whether they approach on foot, upon horseback, or in a vehicle.

To this end my invention consists in certain 15 novel improvements in the construction and combination of devices, all as hereinafter fully set forth and claimed.

In the accompanying drawings, Figure 1 is 20 a perspective view of my improved gate in a partly-closed position, and Fig. 2 is a detail view of the latch.

Like letters refer to corresponding parts in all the figures.

Referring to the drawings, A A' designate 25 the gate posts or standards, suitably secured in the ground. The standard A forms the end of the fence, while the other standard or gate-post is adapted to permit the free passage of the gate. Both of the standards or posts are 30 formed of two pieces connected together so as to leave an open space, a a', between the portions of the post.

A guide-bar, B, connects the upper ends of the two posts A A' together, and on said bar 35 runs a roller, C, which is journaled in the upper end of a standard, D, by which the front end of the gate E is suspended. This standard is extended up from the body of the gate, and is formed of strips connected together 40 lengthwise, so as to form a space, d.

The rear end of the gate is provided with a standard, F, similar in construction to D, the upper end of standard F curving outwardly, as shown. A roller, G, is journaled in said 45 standard, and serves to suspend the rear end of the gate, said roller running upon a second guide-bar, H, lower than guide-bar B, and supported at one end in a post, I, and at the other end in the standard A'. An inclined rod, J, 50 connects the standards D F together.

The gate E is of the usual construction,

formed of horizontal bars e, connected by vertical battens e'. The lower bar of the gate is beveled, as shown, on its under surface or edge, so as to permit the gate to run smoothly in 55 grooved pieces f f', fitted to the ground. One of the pieces, f', is secured between the parts of standard A'.

K designates the gate-latch, which is formed of a horizontal rod pivoted in short standards 60 g g'. This rod is formed of two portions having extending lugs which overlap each other between the standards g g', so that when the gate is shut with force it will not rebound, as the coacting parts of the latch form a spring-like pressure for said latch. The outer end of the latch is formed with a notch, h, which fits over a rod, i, journaled in the standard A.

L L designate posts placed in front of and on a line with standard A', but some distance 70 from it, as shown, said post having arms M extending out therefrom so as to project over the driveway. Pulleys l m are journaled in openings of the arms M, a rope, N, passing from pulley l around a pulley, n, journaled on 75 the end of rod Q, thence to the upper end of standard F at the rear end of the gate, while a similar rope, O, passes from pulley m around a pulley, o, journaled in the standard A', thence to a pulley, P', attached to the rod J, 80 where it connects with the latch K, as shown. Before reaching the pulley P' the ropes O O are connected together, one of the ropes passing down to the latch, while the other rope connects with standard D. As shown, each 85 side of the gate is provided with the posts, arms, pulleys, and ropes of the aforesaid construction and arrangement, in order that the gate may be operated from either side.

The operation of my gate may be readily 90 understood from the foregoing description, taken in connection with the annexed drawings.

As shown, the ropes N O are connected together at q, forming a knot or stop to which a 95 loop, P, is attached. This loop should be arranged a suitable distance from the ground, so as to be convenient for access, and should be used in moving the gate. Suppose the gate to be closed; drawing on rope O brings knot q 100 away from pulley m, and draws said rope O over pulleys m o P'. At the pulley P' the pull-

ing of the rope lifts the latch of the gate by means of a downward extension of said rope. A continuous pull on the rope O by means of loop P will then cause the gate to slide laterally until it reaches the open position. To close the gate pull on the other rope, N, in the same manner, and the gate will be found to close readily. A rod, Q, is secured to the upper part of the standards A A', and serves to guide the standard D of the gate in its sliding movements.

It is obvious that numerous modifications can be made in the construction of the parts without departing from the spirit or scope of my invention.

By my invention I have provided a device that can be pulled open or shut in a direct line without any angular motion, and that will operate with the least possible friction. It can be opened with ease by pulling on the loop P, while, when closed, it cannot be opened by beast or cattle.

Having described my invention, what I claim as new is—

The combination of the standards A A', connected by the guide-bar B, post I, and guide-bar H, with the gate having standards D F, provided with rollers running on said guide-bars, post L, having pulleys l m journaled in an extension thereof, the gate-latch K, formed of two horizontal portions having extended lugs which overlap each other, and pivoted in the gate, and cords passing from the pulleys l m to the standards D F, the front cords connecting with the latch, as herein shown and described.

In testimony that I claim the foregoing as my own I have hereto affixed my signature in presence of two witnesses.

CANTNELL JONES MOORE.
